(57) **CLAIM**

The ornamental design for a cleaning apparatus for dental handpiece, as shown and described.

DESCRIPTION

FIG. 1 is a front elevation of a cleaning apparatus for dental handpiece;

FIG. 2 is a rear elevation thereof;

FIG. 3 is a right side elevation thereof;

FIG. 4 is a left side elevation thereof;

FIG. 5 is a plan view thereof;

FIG. 6 is a bottom view thereof;

FIG. 7 is a perspective view thereof;

FIG. 8 is a perspective view thereof, with the front and top covers opened;

FIG. 9 is a front elevation thereof, with the front cover opened;

FIG. 10 is a right side elevation thereof, with the front cover opened; and

FIG. 11 is a sectional view thereof taken along lines 11-11 in

FIG. 1, with a part of the inside structure omitted; and,

FIG. 12 is a referential view thereof, in a state of use.

The broken lines are included for the purpose of illustrating portions of the cleaning apparatus for dental handpiece that

form no part of the claimed design.
